US00D458921S

(12) **United States Design Patent**
Vuolteenaho et al.

(10) **Patent No.:** **US D458,921 S**
(45) Date of Patent: **** Jun. 18, 2002**

(54) **KEYPAD FOR A HANDSET**

(75) Inventors: **Hanna Vuolteenaho**, Copenhagen (DK); **Jeffrey Higashi**, San Pedro, CA (US)

(73) Assignee: **Nokia Mobile Phones Ltd.**, Espoo (FI)

(**) Term: **14 Years**

(21) Appl. No.: **29/137,976**

(22) Filed: **Mar. 2, 2001**

(51) **LOC (7) Cl.** **14-03**

(52) **U.S. Cl.** **D14/247**
